SURGICAL APPLIANCE

Lawrence M. Smith, Chicago, Ill.

Application June 24, 1933, Serial No. 677,399

3 Claims. (Cl. 128—1)

This invention relates to improvements in surgical appliances, and more particularly to surgical appliances of the character used as an aid to the male organ of generation in the natural performance of its generative function.

The present invention is highly desirable for use in intimate association with the male organ of generation during the natural performance of the sexual act, and contributes in no mean manner to the general health and well being of both the male and female.

While the sexual act itself, and mechanical devices to aid in the proper performance of this act, are not infrequently frowned upon by some for various reasons, nevertheless it is indisputable that the leading physicians, psychiatrists, and sexologists are unanimous in their assertion that the proper and natural performance of the sexual act, especially when consummated with mutual satisfaction, is not only highly beneficial, but in some cases essential, to the general health and well being of the individuals concerned. The converse is equally true, namely that sexual excitation at frequent intervals without culmination is injurious to the human being, often times resulting in neurotic, neurasthenic or even, in some cases, in psychiatric or paranoiacal disorders. Frequently, coition results in excitation or over-excitation without proper culmination to one of the parties, and in most instances this party is the female, the cause of which is, in normal cases, lack of knowledge or regard on the part of the male, which can only be compensated for by the use of the present invention in the absence of proper education, or a natural incongruity residing in a misfit of the male and female genitalia, which can be cured by mechanical means, such as the present invention, except in those rare instances where the female genitalia is too small to accommodate that of the male.

With the foregoing in mind, it is accordingly an object of this invention to provide a surgical appliance which, while capable of aiding greatly in the sustainment of an enfeebled congested organ, is also capable and highly desirable for use as an aid to normal and healthy male organs in performing the act of coition with the proper culmination.

Another object of this invention is the provision of a surgical appliance applicable to the male organ of generation, and which will compensate for ignorance or inability of the male and enable the production of proper excitation and culmination on the part of the female in coition.

It is also an object of this invention to provide a surgical appliance capable of eliminating at least one of the main causes of psychical impotency.

Still another object of this invention is the provision of a surgical appliance for association with the male organ of generation to compensate for a misfit of male and female genitalia without discomfort to either party.

It is still a further object of this invention to provide a surgical appliance attachable to the male organ of generation for use during coition, designed to cause adequate massaging of the most sensitive parts of the female genitalia, thus enabling the production of mutually satisfactory excitation and culmination.

While some of the more salient features, characteristics and advantages of the present invention have been above pointed out, others will become apparent from the following disclosures.

The invention includes these and other features of construction hereinafter described, and shown in a preferred form in the drawing, and more particularly indicated by the claims.

On the drawing:

Figure 1 is a side elevational view of a device embodying principles of the present invention shown applied in proper position to the male organ of generation, the male organ being indicated by dotted lines.

Figure 2 is a top plan view of the device shown in Figure 1.

Figure 3 is a vertical sectional view of the device taken substantially as indicated by the line III—III of Fig. 1.

Figure 4 is a vertical sectional view of the device taken substantially as indicated by the line IV—IV of Figure 1.

As shown on the drawing:

In the illustrated embodiment of this invention, there is shown a tapering wedge-shaped member 5, formed of any desirable or suitable material, but preferably of live rubber of a consistency and resiliency very closely approximating that of a distended male organ of generation. This member may be molded or formed in any other desirable manner. In the preferable form of the member, as the same is illustrated, it will be noted that the member gradually increases in size from front to rear both in a horizontal and vertical plane, the vertical taper being preferably greater than the lateral taper. As indicated in Figure 1, the appliance is preferably disposed on or attached to the male organ of generation 6 near the exterior posterior portion of the organ ad-

- 5 jacent the body 7 of the user, the member 5 being on the upper or dorsal surface of the organ and the organ extending forwardly beyond the appliance.
- 5 10 The member 5 preferably terminates at the rear end thereof in a vertical wall 8 which lies adjacent to or against the body 7 of the user. At the forward portion thereof, the member terminates in a relatively thin lip 9 which intimately contacts the male organ 6. On the underside thereof the member 5 is formed arcuately as indicated at 10 to provide an intimate fit over the male organ. Suitable means may be provided for attaching the appliance to the male organ so that the appliance will, in effect, form an integral enlargement of the organ. In this instance, these means are shown in the form of relatively thin straps 11 and 12, the forward strap 11 being preferably disposed a short distance rearwardly of the lip 9, and the rear strap 12 being preferably wider than the forward strap and having an end thereof in line with the wall 8 of the member 5. These straps 11 and 12 are preferably formed integrally with the member 5 and of substantially the same material so that the straps may be readily stretched to permit the insertion of the male organ and the attachment of the device over the organ as seen in Figure 1 with the appliance on the exterior posterior portion of the organ. If so desired, only the rear strap 12 need be provided.
- 30 15 The straps 11 and 12 are of sufficient elasticity to hold the appliance firmly in position on the male organ and preferably exert a slight restriction upon the dorsal and other veins through which the blood leaves the male organ, without interfering with the arrival of blood to the organ through the deep seated blood vessels. Consequently, the device will aid in maintaining the 20 organ in a congested condition.
- 40 25 The member 5 is also preferably provided with variations in the contour thereof, these variations in the present instance being in the form of integral longitudinally extending ridges 13 and 14 adjacent the forward portion of the device and laterally extending ridges 15 and 16 adjacent the rear portion of the device. It will be noted that these variations in contour provide a relatively smooth yet more pronounced increase in the 30 lateral taper of the appliance at the points mentioned. Consequently, when the device is in use, these variations in contour provide a gradual but definite lateral expansion of the vagina, thus causing contact between the upper portion of the member 5 and the more sensitive parts of the female genitalia, such as the clitoris. If not desired for all cases, the variations may be eliminated leaving a straight line lateral taper on each side, as is preferably the case with the vertical taper. It will therefore be apparent that regardless of the ignorance or thoughtlessness of the male, the act of coition will be consummated

with the proper excitation and culmination on the part of the female. It will also be apparent that the appliance will automatically compensate for substantially any degree of misfit, from a small to even a very gross one, of the respective male and female genitalia, thus removing any cause for embarrassment of the male and eliminating one of the predominant causes of psychical impotency.

5 10 It may be deemed feasible in some cases to mount the appliance on the underside of the male organ or in inverted position with respect to that shown, or attach the device at any other angle, and the provision of a device for such usage is within the contemplation of this invention.

15

From the foregoing, it will be apparent that I have provided a surgical appliance capable of eliminating certain disorders of the human body resulting from a lack of fulfillment in sexual matters, benefiting materially the general health 20 and well being of the individuals concerned. It is also to be noted that the device, while aiding to some extent the rehabilitation of enfeebled powers, nevertheless is preferably used and in many cases recommended by physicians for all 25 periods of sexual life. In addition, it is apparent that the device is efficient in use, economical to manufacture, and very durable.

I am aware that many changes may be made and numerous details of construction may be varied through a wide range without departing from the principles of this invention, and I therefore do not purpose limiting the patent granted hereon otherwise than is necessitated by the prior art.

35

I claim as my invention:

1. In an appliance of the character described, a yielding member having a concave recess in its lower surface extending longitudinally thereof, spaced yielding straps extending from the lower 40 opposite edges of said concave recesses, said member sloping upwardly from its forward end and having laterally sloping parts at its rear end.

2. In an appliance of the class described, a yielding member having a concave recess in its 45 lower surface adapted for receiving the upper rear portion of the male organ of generation and having spaced yielding straps cooperating with said concave recess to maintain said member on said organ, said member sloping upwardly and 50 laterally from its forward end and being considerably shorter than said organ.

3. In an appliance for the male organ of generation, a resilient member having a concave recess in its lower surface and yielding straps co- 55 operating with said recess, said member having a relatively steep upward slope from its front to its rear end and a less lateral slope from its front to its rear end and being designed to extend from the rear to a point slightly forward of 60 the medial point of said organ.

LAWRENCE M. SMITH,
